CIRCUIT BREAKER

Thomas M. Cole, New York, N. Y., and Christopher I. Smith, Newark, N. J., assignors to Cole Electric Products Co. Inc., Long Island City, N. Y., a corporation of New York

Application April 1, 1940, Serial No. 327,150

17 Claims. (Cl. 200—116)

This invention relates to electric circuit breakers and more particularly to circuit breakers constructed and arranged to be actuated in response to current over-loads and also to be actuated manually for making and breaking the circuit.

One object of the invention is the provision of a circuit breaker of the type which is operable automatically in response to current over-loading of the circuit, and which is also manually operable for resetting the same after it is tripped in response to the over-load and for manually opening the same in the absence of an over-load, the construction and arrangement of the several parts of the circuit breaker being such as to facilitate the resetting and manual operations.

Another object of the invention is to provide a circuit breaker of the character described and embodying means for effecting a snap action of the circuit breaker in the operation thereof.

Another object of the invention is to provide a circuit breaker of the type described which is well adapted for alternating current circuits and which is constructed and arranged to operate with a somewhat delayed circuit-breaking action.

A further object of the invention is to provide a circuit breaker of the character described which is simple in construction, inexpensive to manufacture and easy to manipulate in the manual operation thereof.

The above and other objects, features and advantages of the invention will be fully understood from the following description considered with reference to the accompanying drawings.

In the drawings:

Fig. 1 is a sectional view of a circuit breaker embodying the present invention, showing the circuit breaker closed;

Fig. 2 is a view similar to Fig. 1 showing the circuit breaker in tripped condition in response to a circuit over-load;

Fig. 3 is a view similar to Fig. 1 showing the circuit breaker reset, but still open;

Fig. 4 is a sectional view on the line 4—4 of Fig. 1;

Fig. 5 is a top plan view of the circuit breaker, the cover being removed;

Fig. 6 is a top plan view of part of the circuit breaker, the cover being in position;

Fig. 7 is a view similar to Fig. 3, illustrating a modification;

Fig. 8 is a view similar to Fig. 1, showing another form of the invention

Fig. 9 is a view of the circuit breaker shown in Fig. 8 illustrating such breaker in tripped condition;

Fig. 10 is a view of the circuit breaker shown in Fig. 8 and illustrating the circuit breaker in reset condition but with the contacts open, part being broken away for illustrative purposes;

Fig. 11 is a sectional view on the line 11—11 of Fig. 8.

Reference being had now to the drawings in detail and referring first to the form of the invention illustrated in Figs. 1 to 6, the circuit breaker comprises as here shown, a receptacle or base 10, preferably made of "Bakelite" or other suitable insulation material provided with a removable cover or panel 12 of similar material having an opening 14. A switch operating member 16 is pivotally mounted within receptacle 10 and is provided with an operating knob or handle 18 which projects through opening 14 in said receptacle cover 12. Said operating member 16 is also preferably formed of "Bakelite" or other suitable insulation material and has a flat body portion 20 provided at opposite sides thereof with integral cylindrical projections 22 and 24 which engage in bearing portions 26 and 28 formed in the opposite side walls respectively of receptacle 10. Said bearing portions 26 and 28 are formed at the lower ends of grooves 30 which extend to the open end of the receptacle opposite closed end wall 32 thereof. Filler strips 34 are removably positioned in said grooves and engage, at their inner ends, projections 22 and 24, respectively, and are engaged at their outer ends by the inner surface of cover 12. The end of body portion 20 adjacent knob 18 is provided with a laterally extending part 36 engageable with the opposite side edges of opening 14 in freely movable relation thereto. The function of part 36 will be hereinafter explained.

A contact member 38 is fixed to body portion 20 and is mounted in a recess formed by an arc-barrier rib 40 formed integrally with said body portion. Contact member 38 is electrically connected by a flexible conductor 41 to a terminal member 42 disposed in a groove 44, said terminal member 42 being provided with a binding screw 46 for connecting a circuit wire. The other terminal 48 of the circuit breaker is disposed in a groove 48 at the opposite end of receptacle 10, and is provided with a binding screw 50 for connecting a circuit wire.

A contact member 52 is engageable with and disengageable from contact member 38 and for that purpose is mounted for movement in rela-

tion to the latter. Said contact member 50 is fixed to or formed as a part of a lever 52 movable with and in relation to operating member 16, for which purpose said lever 52 is pivotally mounted on projection 24 of the body portion 20 of said operating member. Contact lever 52 is electrically connected by a flexible conductor or pigtail 54 to an over-load tripping device 56 constituted as here shown by an L-shaped bi-metallic strip. One arm 58 of strip 56 is rigidly connected to terminal member 46 and is electrically connected therewith. For this purpose arm 58 can be welded or otherwise secured to member 46. The other arm 60 of said tripping device 56 is arranged for engagement with and disengagement from the notched end 62 of contact lever 52. A spiral spring 64 is connected at one end thereof to switch lever 52 and at its other end is engaged in an opening in one of the side walls of the receptacle, as indicated at 65 in Fig. 4. A flat spring 66 is fixed to the inner surface of end wall 32 and is engaged by a projection 68 on operating member 16.

An arcing chamber member is formed as here shown by a U-shaped fibre strip 70, disposed in grooves 74 formed in the opposite side wall of receptacle 10 at opposite sides of contact members 38 and 50, and by a protective fibre strip 75 carried by body portion 20 of operating member 16 at the side edge thereof, adjacent said contact members 38 and 50. A fibre strip 76 is disposed in vertical grooves 78 in the end wall of receptacle 10 in engagement with terminal member 46 for holding the latter in place.

In the operation of the circuit breaker described above, the parts being in the position illustrated in Fig. 1 which illustrates the closed condition of the circuit breaker, upon the occurrence of a current over-load, bi-metallic strip 56 will disengage the notched end 62 of contact lever 52 thereby permitting spiral spring 64 to move said lever clockwise (viewing Fig. 1) thereby disengaging contact member 50 from contact member 38 and breaking the circuit. The tripped condition of the circuit breaker is illustrated in Fig. 2. When it is desired to reset the circuit breaker preliminarily to the closing thereof, operating member 16 is moved counter-clockwise from the position shown in Fig. 2 to the position illustrated in Fig. 3. During this movement of member 16 the end 36a of part 36 thereof engages lever 52 and moves the same to a position to engage the notched end 62 thereof by the outer edge of arm 60 of the bi-metallic strip of current over-load device 56 and also tensioning spring 64. Finally the circuit breaker is operated to the closed-circuit position, illustrated in Fig. 1, by moving operating member 16 clockwise from the position illustrated in Fig. 3 to the position illustrated in Fig. 1. It will be noted that contact member 50 is stationary during the movement of operating member 16 to close the circuit breaker. It will be understood that the switch can be manually opened while over-load device 60 is in engagement with contact lever 52, which remains stationary, this being accomplished by moving operating member 16 counter-clockwise from the position shown in Fig. 1 to the position shown in Fig. 3, arms 60 of the bi-metallic strip remaining in engagement with the notched end of contact lever 52.

It will be observed that the circuit breaker as thus constructed includes two movable contact members which are relatively movable for opening and closing the circuit breaker under 75

the control of the manually actuated operating member 16 of the over-load responsive or tripping device 56. Also, it will be noted that when the circuit breaker is tripped automatically in response to current over-loads, contact member 38 moves a short distance in the same direction as contact member 50 and thus slows down the circuit-breaking action. This is a desirable feature when the circuit breaking is used in alternating-current circuits as arcing is thereby reduced. Movement of operating member 16 during the tripping of the circuit breaker whereby contact member 38 is also moved, as well as for other purposes hereafter detailed, is effected by spring 66 in engagement with projection 68.

As illustrated in Fig. 6 cover 12 is provided with means to designate the condition of the circuit breaker for which purpose said cover is marked with the legends "on," "off," "reset" and "tripped." Provision is made for releasably holding knob 18 in each of said three indicating positions, one position of said knob 18 at or in engagement with edge 14a of opening 14 adjacent the legends "off" and "reset," obviously indicating that the circuit breaker is open and is in reset condition, ready to be closed when moved to the "on" position. The second position of knob 18 is when the latter aligns with the word "on" and is spaced from the edge 14b of opening 14 marked with the legend "tripped." A third position of knob 18 is when said knob engages the edge 14b of opening 14 marked with the legend "tripped." It will be understood that spring 66 in engagement with projection 68 and operating member 60 is by the shape thereof operable to move said operating member so that the knob 18 thereof engages edge 14b of opening 14 when the circuit breaker is tripped. Similarly in resetting the circuit breaker spring 66 holds operating member 16 in position so that the knob 18 thereof engages edge 14a of the opening 14 of cover 12 in the "reset" and "off" position of the circuit breaker. When the latter is closed, knob 18 is positioned at the legend "on" spaced somewhat from edge 14b of opening 14.

In this last mentioned position of operating member 16 the latter is biased for movement by spring 66 toward edge 14b but such movement is prevented by the engagement of contact members 38 and 50.

In the form of the invention illustrated in Fig. 7, the circuit breaker is constructed and operates substantially in the same way as the circuit breaker described above with references to the Figs. 1 to 6, except that the spiral spring 64a is connected at one end thereof to the body 20 of the operating member 16 as indicated at 65a, instead of being connected as at 65 to the side wall of the receptacle.

In the form of the invention illustrated in Figs. 8 to 11, spring 66 is omitted and in lieu thereof there is utilized a snap action or over-center device comprising a link 80 pivotally connected to the operating member 16a which corresponds to operating member 16 except that it is provided with an eye-forming part 82 in which one end of link 80 is pivotally engaged. The other end of link 80 is slidably engaged in a guide member 84 positioned in slots in the opposite side walls of receptacle 10 and held in position by a fibre filler strip 86 which engages one edge of said guide member 84 and the inner surface of cover 12. A spring 88 is disposed on link 80 and bears at one end thereof on the shouldered end 90 of said link which pivotally engages the

eye-formed part 82 of operating member 16a, the other end of said spring bearing against guide member 84.

The operation of the circuit breaker illustrated in Figs. 8 to 11 will be apparent from the foregoing in comparison with Figs. 1 to 3, the condition of the circuit breaker in Figs. 8, 9, and 10 corresponding to the condition of the circuit breaker in Figs. 1, 2, 3, respectively. It will be noted that in the closed condition of the circuit breaker knob 18 of operating member 16a is spaced slightly from edge 14b of opening 14 and that when the circuit breaker is tripped, knob 18 is moved by spring projected link 80 into engagement with edge 14b and that when the circuit breaker is reset as illustrated in Fig. 10, knob 18 is moved with a snap action by said spring projected link 80 into engagement with the edge 14a of opening 14. Also, it will be noted that the snap action device including spring projected link 80 is effective to move operating member 16a with a snap action during the closing movement thereof, that is, from the position shown in Fig. 10 to the position shown in Fig. 8. Further, it will be understood that when the circuit breaker is tripped by the over-load responsive device 56 contact member 88 follows contact member 86 and thus slows down the circuit-breaking action in response to over-loads substantially in the same way as described above in reference to the form of the invention illustrated in Figs. 1 to 6.

The over-load tripping device 56 is preferably provided with adjusting means. Accordingly as shown in the drawings provision is made for moving the edge of arm 60 longitudinally of notch 62 of lever 52. This is accomplished by means of a set screw 92 which is threaded through an opening 94 in the closed end 32 of receptacle 12 and engages at its inner end with arm 58 of over-load device 56.

It will be understood that in this manner the distance of the edge of arm 60 from the outer end of notch 62 can thus be regulated and that the greater this distance is the greater will be the current required to trip the breaker.

Thus it is seen that the circuit breakers herein shown and described are well adapted to accomplish the several objects of the invention. It will be understood, however, that while we have shown and described several forms of the invention, the latter may be embodied otherwise than as here specifically described or illustrated, and that in each of the forms of the invention herein disclosed, certain changes in the details of construction and in the arrangement of parts may be made and will occur to skilled artisans, in view of the present disclosure. Therefore, we do not wish to be limited to the invention as herein shown or described, except, as may be required by the scope of the appended claims.

Having thus described our invention what we claim and desire to secure by Letters Patent is:

1. In an electric-circuit breaker, a casing, relatively movable companion contact members engageable with and disengageable from each other within said casing, both of said contact members being movable, and an operating mechanism for effecting the engagement and disengagement of said contact members for making and breaking the circuit, respectively, said operating mechanism comprising a manually operable member for effecting movement of both of said contact members, said manually operable member being

mounted for turning movement in said casing and carrying one of said contact members, the other of said contact members being mounted for turning movement concentrically with said manually operable member, said manually operable member having a part projecting outwardly from said casing for the manual operation of the circuit breaker.

2. In an electric-circuit breaker, relatively movable companion contact members engageable with and disengageable from each other, both of said contact members being movable, and an operating mechanism for effecting the engagement and disengagement of said contact members for making and breaking the circuit, respectively, said operating mechanism comprising current-responsive means for controlling movement of one of said contact members, and a manually operable member for effecting movement of the other of said contact members, a casing for said contact members and said operating mechanism, said contact members being mounted on said manually operable member in said casing, said manually operable member having a part projecting outwardly of said casing.

3. In an electric-circuit breaker, a casing, relatively movable companion contact members engageable with and disengageable from each other, both of said contact members being movable, and an operating mechanism for effecting the engagement and disengagement of said contact members for making and breaking the circuit, respectively, said operating mechanism comprising a manually operable member for effecting movement of both of said contact members, said manually operable member being mounted for turning movement and carrying one of said contact members, the other of said contact members being mounted for turning movement concentrically with said manually operable member, current-responsive means, and means operable under the control of said current-responsive means for automatically disengaging said contact members, said manually operable member being mounted for turning movement in said casing and carrying one of said contact members, the other of said contact members being mounted for turning movement concentrically with said manually operable member, said manually operable member having a part projecting outwardly from said casing for the manual operation of the circuit breaker.

4. In an electric-circuit breaker, relatively movable companion contact members engageable with and disengageable from each other, both of said contact members being movable, and an operating mechanism for effecting the engagement and disengagement of said contact members for making and breaking the circuit, respectively, said operating mechanism comprising a movable member on which one of said contact members is mounted, a movable arm on which said other contact member is carried, said arm being mounted on said movable member for movement in relation thereto, current-responsive means releasably engagable with said arm for preventing movement of said arm in one direction, and means operable under the control of said current-responsive means for moving said arm in the said direction for disengaging said contact members.

5. In an electric-circuit breaker, relatively movable companion contact members engageable with and disengageable from each other, both of said contact members being movable, and an

operating mechanism for effecting the engagement and disengagement of said contact members for making and breaking the circuit, respectively, said operating mechanism comprising a movable member on which one of said contact members is mounted, a movable arm on which said other contact member is carried, said arm being mounted on said movable member for movement in relation thereto, current-responsive means including a bi-metallic strip engageable with said arm to hold the latter against movement in one direction and disengageable from said arm to permit movement thereof in said direction, and means automatically operable to move said arm in said direction upon disengagement of said bi-metallic strip therefrom for disengaging said contact members.

6. In an electric-circuit breaker, a movable operating members, a contact member movable to closed and open positions under the control of said operating member, a pivotally mounted arm, a companion contact member carried by said arm at one side of its pivot and movable to closed and open positions, and means engageable with said arm at the other side of its pivot for releasably holding said companion contact member substantially stationary during the movement of said first mentioned contact member to said closed and open positions thereof.

7. In an electric-circuit breaker, a movable operating member, a contact member movable to closed and open positions under the control of said operating member, a companion contact member movable to closed and open positions, both of said contact members being carried by said operating member, and means for releasably holding said companion contact member substantially stationary during the movement of said first mentioned contact member to said closed and open positions thereof, said last mentioned means including current-responsive means for releasing said companion contact member for movement to said open position thereof.

8. In an electric-circuit breaker, a movable operating member, a contact member movable to closed and open positions under the control of said operating member, a companion contact member movable to closed and open positions, both of said contact members being carried by said operating member, and means for releasably holding said companion contact member substantially stationary during the movement of said first mentioned contact member to said closed and open position thereof, said last mentioned means including current-responsive means for releasing said companion contact member for movement to said open position thereof, said operating member being operable to move said companion contact member, after the release thereof, for re-setting the same in said first mentioned position thereof for engagement by said first mentioned contact member.

9. In an electric-circuit breaker, a receptacle, an operating member of insulation material pivotally mounted in said receptacle and having a manually operable part accessible externally of the receptacle for actuating said member, a contact member carried by said operating member, an arm pivotally mounted in said receptacle on a pivot concentrically with said operating member, a contact member carried by said arm and movable therewith, said contact members being engageable with and disengageable from each other under the control of said operating

member, and means for actuating said arm to disengage said contact members.

10. In an electric-circuit breaker, a receptacle, an operating member of insulation material pivotally mounted in said receptacle and having a manually operable part accessible externally of the receptacle for actuating said member, a contact member carried by said operating member, an arm pivotally mounted in said receptacle on a pivot concentrically with said operating member, a contact member carried by said arm and movable therewith, said contact members being engageable with and disengageable from each other under the control of said operating member and a current-responsive tripping mechanism associated with said arm operative to cause the disengagement of said contact members independently of the actuation of said operating member by said manually operable part.

20 11. In an electric-circuit breaker, relatively movable companion contact members engageable with and disengageable from each other, both of said contact members being movable, and an operating mechanism for effecting the engagement and disengagement of said contact members for making and breaking the circuit, respectively, said operating mechanism comprising a manually operable pivotally movable member for effecting movement of both of said contact members, one 25 of said companion contact members being carried by said pivotally movable member, and spring means engageable with said manually operable member effective to oppose movement thereof and also to assist in the movement 30 thereof.

35 12. In an electric-circuit breaker, a movable operating member, a contact member movable to closed and open positions under the control of said operating member, a companion contact member movable to closed and open positions, said first mentioned contact member being carried by said operating member, and means for releasably holding said companion contact member substantially stationary during the movement 40 of said first mentioned contact member to said closed and open positions thereof, and an over-center spring device including a part of said operating member and a spring projected member connected to said part operable to complete the movement of said manually operable member after a partial movement thereof.

45 13. In an electric-circuit breaker, a movable operating member, a contact member movable to closed and open positions under the control of said operating member, a companion contact member movable to closed and open positions, said first mentioned contact member being carried by said operating member, and means for releasably holding said companion contact member substantially stationary during the movement 50 of said first mentioned contact member to said closed and open positions thereof, and an over-center spring device operable to complete the movement of said manually operable member after a partial movement thereof, comprising a spring projected link pivotally connected to said manually operable member.

55 14. In an electric-circuit breaker, a pivotally movable operating member, a contact member movable to closed and open positions under the control of said operating member, a companion contact member movable to closed and open positions, said first mentioned contact member being carried by said operating member, and means for releasably holding said companion contact mem-

ber substantially stationary during the movement of said first mentioned contact member to said closed and open positions thereof, said last mentioned means including current-responsive means for releasing said companion contact member for movement to said open position thereof, and spring means engageable with said operating member effective to oppose movement thereof and also to assist in the movement thereof.

15. In an electric-circuit breaker, a movable operating member, a contact member movable to closed and open positions under the control of said operating member, a companion contact member movable to closed and open positions, said first mentioned contact member being carried by said operating member, and means for releasably holding said companion contact member substantially stationary during the movement of said first mentioned contact member to said closed and open position thereof, said last mentioned means including current-responsive means for releasing said companion contact member for movement to said open position thereof, and an over-center spring device operable to complete the movement of said operating member in both the opening and closing operations thereof after movement thereof is initiated.

16. In an electric-circuit breaker, relatively movable companion contact members engageable with and disengageable from each other, both of said contact members being movable, and an operating mechanism for effecting the engagement and disengagement of said contact members for making and breaking the circuit, respectively, said operating mechanism comprising current-responsive means for controlling movement of

one said contact members, said operating means including a manually operable member for effecting movement of the other of said contact members, both of said contact members being mounted on said manually operable member and means for moving said other contact member in the same direction as said one contact member during part of the movement of the latter to circuit-opening position under the control of said current-responsive means.

17. In an electric-circuit breaker, relatively movable companion contact members engageable with and disengageable from each other, both of said contact members being movable, and an operating mechanism for effecting the engagement and disengagement of said contact members for making and breaking the circuit, respectively, said operating mechanism comprising a movable member on which one of said contact members is mounted, a movable arm on which said other contact member is carried, said movable arm being also mounted on said movable member of the operating mechanism, current responsive means for preventing movement of said arm in one direction, and means operable under the control of said current-responsive means for moving said arm in the said direction for disengaging said contact members, and means for moving said movable member and said contact mounted thereon in the same direction as said arm during part of the movement of the latter to circuit-opening position under the control of said current-responsive means.
